Des. 191,279
Patented Sept. 5, 1961

191,279

LAMP BASE OR THE LIKE

Louis O. Dennis, 3944 Clermont St., New Orleans, La.

Filed Sept. 1, 1959, Ser. No. 57,400

Term of patent 14 years

(Cl. D48—20)

FIG. 1

FIG. 2

FIG. 1 is an elevational view of a lamp base or the like embodying my new design; and

FIG. 2 is a top plan view thereof with the socket member omitted for convenience of illustration.

The dominant features of my design reside in the portions shown in full lines.

I claim:

The ornamental design for a lamp base or the like, substantially as shown and described.
